US0D1078427S

(12) **United States Design Patent** (10) **Patent No.:** **US D1,078,427 S**
(45) **Date of Patent:** **** Jun. 10, 2025**

(54) **ELECTRIC HYDRAULIC TOOL**

(71) Applicant: **Maxell Izumi Co., Ltd.**, Matsumoto (JP)

(72) Inventor: **Takahito Hirabayashi**, Matsumoto (JP)

(73) Assignee: **MAXELL IZUMI CO., LTD.**, Matsumoto (JP)

(**) Term: **15 Years**

(21) Appl. No.: **29/920,798**

(22) Filed: **Dec. 13, 2023**

(30) **Foreign Application Priority Data**

Oct. 31, 2023 (JP) ..... 2023-022639 D

(51) **LOC (15) Cl.** **08-03**

(52) **U.S. Cl.**

USPC **D8/61**

CLAIM

The ornamental design for an electric hydraulic tool as shown and described.

DESCRIPTION

FIG. 1 is a left side elevation view of an electric hydraulic tool embodying my new design;

FIG. 2 is a right side elevation view thereof;

FIG. 3 is a rear elevation view thereof;

FIG. 4 is a front elevation view thereof;

FIG. 5 is a top plan view thereof;

FIG. 6 is a bottom plan view thereof;

FIG. 7 is a top-front-left side perspective view thereof;

FIG. 8 is a bottom-rear-right side perspective view thereof;

FIG. 9 is a bottom-front-left side perspective view thereof;

FIG. 10 is a top-rear-right side perspective view thereof;

FIG. 11 is a top-rear-left side perspective view thereof;

FIG. 12 is a bottom-front-right side perspective view thereof;

FIG. 13 is a bottom-rear-left side perspective view thereof; and,

FIG. 14 is a top-front-right side perspective view thereof. The broken lines depict portions of the electric hydraulic tool that form no part of claimed design.

1 Claim, 14 Drawing Sheets
